UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed February 14, 1924. Serial No. 692,856.

To all whom it may concern:

Be it known that I, ALONZO E. RHOADES, a citizen of the United States, residing at Hopedale, in the county of Worcester and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms and more particularly to the intermittent type of feeler mechanisms wherein the feeler is held in an inoperative 15 position for periods of time and is released periodically to the performance of its feeling function during weaving with the same supply of filling in the shuttle.

In feeler mechanisms of the intermittent 20 type, and especially when weaving with certain kinds or characters of filling, it is desirable that the feeler be moved into a position such that it will not contact with the filling on detecting beats, and one of the 25 objects of the present invention is to provide a feeler mechanism of the type indicated, wherein means of simple and effective construction are provided for moving and holding the feeler in a frontward inoperative 30 position during its periods of inactivity and releasing it at intervals to its periods of activity.

The novel features of the invention and new combination of parts will best be made 35 clear from the following description and the accompanying drawings of one good practical form of the invention.

In the drawings:

Fig. 1 is a perspective view of a loom at 40 the feeler side, showing a feeler mechanism containing the present invention;

Fig. 2 is an enlarged perspective view showing the feeler released to the performance of its feeling function;

Fig. 3 is a side elevation showing the feeler mechanism with the feeler withdrawing and holding detent in intermediate position for engagement with the feeler when it is moved frontwardly by a working sup-

ply of filling in the shuttle on a detecting 50 beat;

Fig. 4 is a view similar to that of Fig. 3, but showing the feeler as having been withdrawn frontwardly by the detent and held in its inoperative position; and 55

Fig. 5 is a view of the detent controller and its actuating means.

The feeler mechanism of the present invention is herein shown as associated with means for effecting replenishment of filling 60 when that in the shuttle is substantially exhausted on a detecting beat, but the replenishing mechanism is not illustrated because it may be of any usual type and is now well understood, and the details thereof 65 form no essential part of the invention. As shown, the feeler is of the inclined type, that is, it enters the shuttle in a direction inclined to the longitudinal axis thereof and is displaced in a direction longitudinally of 70 the shuttle to call the change by the frontward pressure upon it when the filling is substantially exhausted. While this type of feeler is well adapted for cooperation with the present invention, other forms or 75 types of feelers may be employed with advantage.

The loom frame 1 has brackets 2, Fig. 1, in which is supported the transverse or rock shaft 3 which extends across the loom and 80 is operatively associated with the means for effecting replenishment of the filling, as usual. Secured to and rising from the transverse or rock shaft 3 is an arm 4 to which is pivoted at 5 the rearwardly extending member 6 having pivotally connected thereto at 7 the finger 8, the rear end portion of which is adapted at times to be engaged by the operating member 9 which may be associated with or formed as part 85 of the cam follower. Above the finger 8 is an arm 10 which overlies the horizontal arm 11 of a bell crank lever pivoted at 12 to a bracket 13 supported by the loom frame. The other arm of the bell crank lever is 90 connected to a transmitter 14, the construction being such that should the transmitter be moved by the feeler when it calls for a 95

change of filling, the member 8 will be placed in the path of the operating member 9 and filling replenishment be effected. The transmitter and associated details described 5 may be of any usual type and construction for effecting replenishment of filling when the feeler calls for replenishment.

Extending from the shipper stand 15 is an arm 16 to which is adjustably secured 10 the feeler supporting bracket 17 by means of a bolt or similar device 18. The feeler stand 19 is adjustably secured to the bracket 17 by a bolt or other means 20.

In the present instance of the invention, 15 the feeler is of the inclined type and is mounted on the feeler stand for movement longitudinally of the shuttle by the forward pressure of a surface within the shuttle when the filling is substantially exhausted on a detecting beat, and while this form of feeler may be advantageously employed, the invention is not restricted to its use, as other forms of feelers may be associated therewith.

25 The feeler stand 19 has a rear bearing portion 21 containing a guideway for a slide 22 which is connected to the transmitter 14, and is provided with a slot through which the feeler 23 extends and in 30 which it may have normal laterally displacing movement. The slide 22 may be conveniently held in its guideways by a cap-plate 24 secured to the rear bearing by screws 25.

35 The frontwardly extending stem portion 26 of the feeler passes through a front bearing 27 shown as formed of a swivel block, and between the front bearing 27 and a projection or bridge 28 secured to the feeler 23 is a spring 29 normally acting upon the feeler to move it rearwardly into its feeling position.

The parts so far described are or may be 45 substantially the same as the similar parts in the patent to Edward S. Stimpson, No. 1,309,226 dated July 8, 1919, to which reference may be had for more full disclosure of the detailed mechanism, and the rear end portion of the feeler may if desired be provided with teeth 30 for engagement with the filling 31 on the filling carrier or bobbin 32, as usual.

55 The lay 33 is provided with the shuttle box 34 having a slot 35 in its front wall, and the shuttle 36, which may be of usual type, is likewise provided with a slot 37 and adapted to register with the slot 35 when the shuttle is properly positioned in the shuttle box, so that the feeler may enter 60 the shuttle and feel for the filling.

In accordance with the present invention, 65 the feeler is to be held in a frontward inoperative position for periods of inactivity and to be released at intervals to the per-

70 formance of its feeling function, and then 75 returned to its frontward or inoperative position should the feeler find a working supply of filling in the shuttle on a detecting beat. In the present invention this result is secured by means of a detent or pivoted pawl under the influence of a controller and adapted to engage a projection on the feeler to withdraw the feeler frontward under the dictates of the controller and hold it in withdrawn frontward position during its periods of inactivity.

75 As one good means for carrying out this 80 feature of the invention, the detent is mounted upon the feeler stand with capacity for pivotal and bodily movements to 85 perform its withdrawing and holding functions. As shown, the feeler stand is provided with the bearings 38 which may be constituted as supports for the detent and conveniently associated with the cap plate 24 through the risers 39. Each of the bearings, 38, of which there may be two, as indicated, is provided with an inclined slot 40 into which projects a pin 41 extending from the detent 42, the construction being such 90 that the detent 42 may have pivotal movement relative to the bearings 38 and also a bodily movement towards and from the front of the loom, the inclined slot 40 acting at such time to define the vertical position of the detent. The rear end portion of the detent 42 has a tooth 43, which is adapted to engage a projection or tooth 44 extending from the feeler to thereby withdraw the 95 feeler into a frontward inoperative position and hold it during its periods of inactivity. While the bearing 38 is shown as provided with the slots 40 into which the pin 41 of the detent extends, a reversal 100 of this arrangement might of course be employed without departing from the present invention.

105 Extending frontwardly from the feeler stand is a bracket or arm 45 to which is pivoted at 46 a bell crank lever, one arm 47 of which is connected to the detent 42 at 48, and the other arm 49 of which is connected at 50 with a rod 51 which constitutes a part of the detent controller. The rod 51, 110 as indicated in Fig. 5, extends downwardly from the feeler stand and is connected at 52 to a pivoted member or lever 53 pivotally supported at 54 on the bracket 55 appropriately secured to the loom frame.

115 The lever 52 is normally under the influence of a spring 56 and is limited in its movement under spring control by a stop 57, Figs. 1 and 5, and when the lever 53 is resting upon the stop 57, the detent 42 will be in its frontward holding position 120 for maintaining the feeler in an inoperative position out of contact with the filling on detecting beats.

In accordance with the present invention, the feeler is to be released at intervals, and to this end means are provided for periodically actuating the lever 53. Such means 5 may be conveniently associated with the take-up mechanism, although this is not necessary and it might be otherwise constituted as a member of a moving train of mechanism associated with other parts of 10 the loom. As shown, the lever 53 has an extension 58, the end 59 of which is in the path of an actuator 60, shown as connected to one of the spokes 62 of the ratchet wheel. The actuator 60 may be detachably connected 15 to the ratchet wheel as by a nut 63, Fig. 5, which may be passed through an opening 64 in one of the spokes of the ratchet wheel, and one or more of such actuators may be employed if desired.

20 The actuator 60 has a trip portion 65 and a dwell portion 66 for cooperating with the end 59 of the lever 53 and for the purpose of first tripping the detent from holding engagement with the feeler, then permitting 25 the detent to move to an intermediate position during the passage of the dwell portion 66 of the actuator under the end 59 of the lever 53, and then freeing the lever 53 to the impulse of the spring 56 to thereby withdraw 30 the feeler from engagement with the detent into its frontward position. Inasmuch as the means for withdrawing the feeler from its cooperative relation with the filling is controlled from a train of mechanism 35 which may have no timed relation with the lay movements, or wherein such timed relation is not easily accomplished to accurately insure that the feeler shall perform its feeling function after it has been freed to its 40 period of activity until after a detecting beat of the lay, it is desirable that the means for withdrawing the feeler frontwardly be caused to dwell in its feeler engaging position until after the feeler has been moved 45 frontwardly on a detecting beat, thus insuring that the feeler shall during its period of activity detect the condition of the filling in the shuttle. The present invention therefore contemplates, as herein above stated, a 50 dwell device which will suspend the operative movement of the means for moving the feeler to its frontward inoperative position until after the lay has made a detecting beat or the feeler has been moved frontwardly by 55 engagement with the filling in the shuttle, and in the present instance this functional dwell of the means of withdrawing the feeler is accomplished through the dwell portion 66 of the actuator 60.

60 Assuming that the detent 42 is in the position indicated in Fig. 4, and engaged with the feeler for holding it in an inoperative frontward position, the first action of the actuator 60 as the end 59 of the lever 53

is engaged by the trip portion 65 of the actuator is to cause the detent to move bodily in a rearward direction in the slots 40 of the bearing 38 and also to pivotally move in a clockwise direction, viewing Fig. 4, thereby freeing the feeler from the control of the detent and permitting it to perform its feeling function. As the dwell portion 66 passes under the end 59 of the lever 53 the detent will be moved bodily and pivotally into an intermediate position and there dwell, as indicated in Fig. 3, and as the feeler is moved frontwardly by a working supply of filling on a detecting beat, the projection 44 on the feeler will pass frontwardly of the tooth 43 on the detent, as indicated in Fig. 3, and as the lay goes back the feeler will be held by the detent from following it. This condition is well illustrated in Fig. 3 wherein the working supply of filling 31 on the filling carrier or bobbin 32 has moved the feeler frontwardly to its first frontward position, as indicated by dotted lines in Fig. 3, thereby causing the projection 44 to move frontwardly of the tooth 43 of the detent, the parts having sufficient "give" or yield for this purpose. As the lay goes back, the detent will hold the feeler in the frontward position to which it has been moved by the filling and thereafter as the dwell portion 66 of the actuator passes out of engagement with the end 59 of the lever 53, the detent will be moved bodily in a frontward direction and also pivotally into the position indicated in Fig. 4, to thereby withdraw and hold the feeler in its inoperative position during its period of inactivity, at which time the feeler does not strike the filling, as indicated in Fig. 4. The positive connection of the detent through the bell crank lever described to the rod 51 effects a positive movement of the detent both bodily and pivotally relative to the detent bearings and causes the detent to act reliably in the performance of detent functions.

Should a working supply of filling not be present in the shuttle on a detecting beat during a period of activity of the feeler, the latter will not be moved frontwardly sufficiently far to engage the projection 44 with the tooth 43 of the detent, but the feeler will remain in its feeling position and when the filling is substantially exhausted on a detecting beat the feeler will call for the change of filling by movement of the slide 22 and transmitter 14.

It will be noted from the construction described, that the detent 42 has three movements—one, a bodily movement towards and from the front of the loom, another a pivotal movement, and another a movement bodily towards and away from the feeler, and that when the detent is tripped by the controller to free the feeler to the performance of its

feeling function, it partakes of such bodily movement in a rearward direction and also a pivotal movement under the positive action of the bell crank.

5. What is claimed is:

1. In a feeler mechanism for looms, the combination of a feeler, a pivotal detent mounted for movement of its pivotal point towards and from the front of the loom for moving the feeler frontwardly out of cooperative relation with the filling and holding it at rest for a period of time and then releasing it to the performance of its feeling function, and means for operating the detent that the feeler may have periods of activity and be moved into a position of inactivity at intervals during weaving with the same supply of filling in the shuttle.
2. In a feeler mechanism for looms, the combination of a feeler, a feeler withdrawing and holding detent pivotally mounted on the feeler stand for movement of its pivotal point towards and from the front of the loom to withdraw the feeler from cooperative relation with the filling and maintain it at rest, and means to operate the detent to free the feeler at intervals that the feeler may have periods of activity and periods of inactivity during weaving with the same supply of filling in the shuttle.
3. In a feeler mechanism for looms, the combination of a feeler, a feeler withdrawing and holding detent having a pivotal support on the feeler stand and mounted for movement of its pivotal point towards and from the front of the loom to withdraw the feeler and hold it in retracted position, means for operating the detent to free the feeler at intervals to the performance of its feeling function and then withdraw and hold the feeler again in retracted position when a working supply of filling is in the shuttle on a detecting beat that the feeler may have periods of activity and periods of inactivity during weaving with the same supply of filling in the shuttle.
4. In a feeler mechanism for looms, the combination of a feeler, a detent for holding the feeler in frontward position, a support on the feeler stand with relation to which the detent has a pivotal and bodily movement towards and from the front of the loom to withdraw the feeler and hold it in retracted position, and a controller for operating the detent to free the feeler at intervals to the performance of its feeling function and then withdraw it in frontward retracted position that the feeler may have periods of activity and inactivity during weaving with the same supply of filling in the shuttle.
5. A feeler mechanism, comprising, in combination, a feeler, a detent for holding

the feeler in inoperative position, a support on the feeler stand for the detent with relation to which it has a pivotal movement, a bodily movement towards and from the front of the loom, and a movement towards and from the feeler, and means for operating the detent to free the feeler at intervals and then move it to an inoperative position that the feeler may have periods of activity and periods of inactivity during weaving.

6. A feeler mechanism, comprising, in combination, a feeler stand, a feeler, a feeler holding detent, an inclined pin and slot bearing for the detent, and means for moving the detent in a direction towards and from the front of the loom in said bearing and also pivotally with relation thereto to free the feeler at intervals during weaving with the same supply of filling in the shuttle.

7. In a feeler mechanism for looms, the combination of a feeler, a detent for moving the feeler to and holding it in an inoperative position, an inclined pivotal support for the detent with reference to which it has pivotal movement and bodily movement towards and from the front of the loom, and means for operating the detent at intervals to free the feeler to the performance of its feeling function and then move the feeler again to its inoperative position during weaving with the same supply of filling in the shuttle.

8. In a feeler mechanism for looms, the combination of a feeler, a feeler withdrawing and holding detent, a support for the detent with reference to which it has pivotal movement and bodily movement towards and from the front of the loom, a controller for the detent, and positive connections between the detent and controller for imparting positive pivotal and bodily movements to the detent to free the feeler at intervals and withdraw and hold it in inoperative position thereafter during weaving with the same supply of filling in the shuttle.

9. In a feeler mechanism for looms, the combination of a feeler, a detent for holding the feeler in an inoperative position, a bearing for the detent with relation to which it has pivotal movement and bodily movement towards and from the front of the loom, a detent controller for operating the detent, and positive connections between the controller and detent for imparting a rearward and pivotal movement to the detent to free the feeler at intervals during weaving with the same supply of filling in the shuttle.

10. In a feeler mechanism for looms, the combination of a feeler, a detent for holding the feeler in a frontward inactive po-

sition and mounted for pivotal movement and bodily movement towards and from the front of the loom, a controller positively connected to the detent, and an actuator for operating the controller to free the feeler to the performance of its feeling function, then cause the detent to be moved to an intermediate position and dwell for

engagement with the feeler should it be moved frontwardly by a working supply 10 of filling on a detecting beat and then further withdraw the feeler frontwardly to its inactive position.

In testimony whereof, I have signed my name to this specification.

ALONZO E. RHOADES.
